UNITED STATES PATENT OFFICE.

ARTHUR EDWIN LEIGH SCANES, OF ASHTON-ON-MERSEY, ENGLAND, ASSIGNOR TO
WESTINGHOUSE ELECTRIC AND MANUFACTURING COMPANY, A CORPORATION OF
PENNSYLVANIA.

JECTOR CONDENSING APPARATUS.

Application filed November 24, 1920. Serial No. 426,252.

To all whom it may concern:

Be it known that I, ARTHUR EDWIN LEIGH SCANES, a subject of the King of Great Britain and Ireland, and a resident of 5
Strathfield, Harboro Road, Ashton-on-Mersey, in the county of Chester, England, have made a new and useful Invention in Ejector Condensing Apparatus, of which the following is a specification.

10 This invention relates to apparatus for condensing vapor such as steam and extracting non-condensable gases such as air from an enclosed receptacle, for example, a steam condenser.

15 One well-known apparatus of this type employs a water jet which is broken up by a reversely driven turbine and another takes the form of an ejector utilizing a water jet or jets. The Leblanc rotary ejector and the 20 Koerting ejector are respectively examples of these two types of apparatus, and for convenience will be hereinafter referred to by these names.

It has been found that with ejectors of the 25 Leblanc type, although their air extracting capacity is high, a large amount of power is absorbed in rotating the turbine wheel. Conversely the power taken by ejectors of the Koerting type is usually comparatively 30 small—but the air extracting capacity of this type of ejector, even when provided with multiple nozzles, is low.

The present invention has for its object 35 to provide improved apparatus in which the disadvantages inherent in both the above mentioned types of apparatus are overcome.

According to this invention, the apparatus 40 comprises a central jet of water supplied by means of a reversed turbine wheel of the Leblanc type surrounded by a plurality of jets of water of the Koerting ejector type. By suitably arranging the cones within the ejector the vapor to be condensed is first forced through the plurality of water jets 45 and then such vapor and gases as are not condensed thereby are removed by the water jet furnished by the turbine wheel.

In the accompanying drawing, Fig. 1 is 50 a sectional elevation somewhat diagrammatic of a condensing apparatus constructed in accordance with the invention, and Fig. 2 is a plan of the same.

A casing 1 has at its upper part a flange 2 by means of which it may be connected to

an exhaust pipe or other receptacle from 55 which steam or other condensable and non-condensable vapors are to be extracted and condensed or removed. Said casing is supported on a diffuser 3 and encloses the housing 4 of a rotary ejector of the well known Leblanc type and an annular chamber 5 provided with a ring of nozzles 6. Injection water is supplied to the annular chamber 5 through the inlet pipe 7. The housing 4 encloses the rotary impeller 8 and the 60 internal water chamber 9 of the Leblanc ejector which are of the ordinary construction, the impeller 8 being rotated and the water chamber 9 being supplied with sealing water by any usual means. For convenience 70 of illustration, only a few blades 10 are shown on the impeller but its entire circumference will be provided with blades in the customary manner. Within the casing 1 and near its lower part are supported in any suitable manner an inner ejector cone 11 and an outer cone 12, the jets from the ejector nozzles 6 passing into the annular chamber between the cones and the broken water jet indicated at 13 which is delivered 75 from the impeller 8 being received in the inner cone 11.

It will be readily seen that the mixed 80 gases and vapors from the receptacle will pass down the upper part of the casing 1 and through the water jets from the nozzles 6 and such vapor and gases as are not 85 condensed thereby will be removed by the broken water jet 13, the whole being ultimately forced through the cones into the 90 diffuser 3.

The proportion of water passed through 95 the turbine wheel compared with that passed through the nozzles of the water jets may be varied in accordance with the capacity which it is desired the apparatus shall have for extracting air and non-condensable gases the relative proportion of water passed through the turbine wheel being increased to increase the air extracting capacity of the 100 apparatus.

Where a natural head of water is available 105 it may be utilized for supplying the water to the nozzles of the water jets and the only power required will be that necessary for rotating the turbine wheel supplying the broken water jet, but where no natural head is available it will be necessary

to employ a suitable pump for providing the necessary head. It is sometimes convenient to arrange a centrifugal pump on the same shaft as the turbine wheel, this pump giving the necessary head to the water jets. In some cases, the centrifugal pump may also be used to prime the reverse turbine when starting.

Having now particularly described and ascertained the nature of my said invention and in what manner the same is to be performed, I declare that what I claim is:—

1. In a condensing apparatus the combination, with a device of the Leblanc rotary 15 ejector type, the broken water jet of which is supplied to a central cone, of a plurality of nozzles the jets from which are directed into an annular chamber surrounding said central cone substantially as and for the 20 purpose specified.

2. In an ejector, a chamber, means for delivering a substantially annular stream of fluid through the chamber, means for delivering a broken water jet centrally of the 25 annular stream of fluid, and means for uniting and discharging the jets and entrained fluids from the chamber.

3. In an ejector, a chamber, an annular series of jets discharging into said chamber, 30 an annular combining tube within the chamber into which the jets discharge, a Leblanc rotary ejector arranged to discharge broken water jet centrally of the annular series of jets into a central cone, and a diffuser communicating with the chamber and arranged 35 to receive the jets.

4. The method of evacuating gases from a region of low pressure comprising entraining the gases to be evacuated in an annular 40 stream of fluid, entraining any of the gases not entrained in the annular stream of fluid

in a broken jet of water, internally disposed with respect to said annular stream, uniting the stream of fluid and the water jet, together with their entrained fluids, and discharging the united fluids into a region of higher pressure. 45

5. In an ejector, a chamber having inlet means for a fluid to be entrained, means for delivering a substantially annular stream 50 of entraining fluid through said chamber, means for delivering a broken water jet centrally of said annular stream, and means for uniting and discharging the said stream and the said jet, together with their entrained fluids, from the chamber. 55

6. In an ejector, a chamber, means for delivering a substantially annular stream of entraining fluid through said chamber, means for admitting fluid to be entrained to 60 said chamber in such manner as to substantially surround the said annular stream, means for delivering a broken water jet centrally of said annular stream and means for uniting and discharging the said stream and 65 the said jet together with their entrained fluids from the chamber.

7. The method of evacuating gaseous fluids from a region of low pressure comprising entraining the gaseous fluids to be 70 evacuated in a hollow stream of motive fluid, discharging a broken liquid jet inferiorly of said hollow stream of motive fluid, uniting the stream of motive fluid and the broken liquid jet together with the entrained fluids, and discharging the united fluids into a region of higher pressure. 75

In testimony whereof, I have hereunto subscribed my name this 9th day of November, 1920.

ARTHUR EDWIN LEIGH SCANES,
